Primary Examiner — Cynthia Underwood(74) *Attorney, Agent, or Firm* — Patent Law & Venture Group; Gene Scott(57) **CLAIM**

An ornamental design for a decorative feedthrough, as shown and described.

DESCRIPTION

FIG. 1 is a perspective view of my new design as seen from a first direction;

FIG. 2 is a top plan view thereof;

FIG. 3 is a bottom plan view thereof; and,

FIG. 4 is a further perspective view thereof shown with a decorative nut and washer in extended positions, and as seen from a second direction opposite said first direction.

The broken lines shown in FIGS. 1 and 4 illustrate a tube engaged within the feedthrough and which forms no part of the claimed design but is shown to merely indicate how the design is used.
